UNITED STATES PATENT OFFICE

2,471,755

STEAM-AIR-THERMAL POWER PLANT

Werner Karrer, Zurich, Switzerland, assignor to
 Maschinenfabrik Oerlikon, Zurich-Oerlikon,
 Switzerland

Application March 1, 1945, Serial No. 580,438
 In Switzerland January 5, 1944

Section 1, Public Law 690, August 8, 1946
 Patent expires January 5, 1964

5 Claims. (Cl. 60—49)

1

In steam-gas-thermal power plants any increase of the efficiency by an intermediate heating of the air working in the turbine and by increasing the amount of air over that necessary for the combustion is very limited. To increase the efficiency of a turbine plant it would seem feasible to introduce more fuel to heat a larger amount of air. By calculation it has been found that by doing so the temperature of the gases of combustion after leaving the steam boiler would be dangerously high and might injure the material of the steam superheater or air heater. If the temperature remains within the allowable limits the heat after leaving the steam boiler would not suffice to heat a larger amount of air.

The object of the present invention is to provide means to increase the efficiency of power plants of the character described by mixing hot gases with the gases of combustion after the same have left the steam boiler. The hot gases may be taken from the combustion chamber in advance of the steam boiler or the said hot gases may be produced in a separate chamber of combustion.

In the accompanying drawing two embodiments of my invention are shown by way of examples each in sectional elevation in a diagrammatical manner.

In Fig. 1 of the drawings 1 denotes a tubular steam boiler to which fresh water is fed by a feed line 2. The boiler 1 is arranged above a grate 3. The steam leaving the boiler 1 passes through a superheater 4 arranged in the path of the combustion gases. The steam superheated in the superheater 4 passes through a pipe 5 to a steam turbine 6 and from there to a condenser 7. The steam turbine 6 is a prime mover destined to drive any machine 9 doing mechanical work. The feed water is fed to the boiler 1 by any suitable pump 8. The coil 12 denotes a device to heat air and the heated air drives a turbine 13 by which a compressor 14 and a machine 15 for performing useful work is driven.

The amount of air introduced into the air turbine plant is larger than the amount of air which is necessary to keep up the combustion of the fuel to produce steam in the boiler 1. A portion of the exhaust air from the turbine 13 passes by pipe 16 under the grate 3. Through a pipe 17 the remaining air is led to a feed water heater 18. If not all the heat of the remaining air is used to pre-heat the feed water the surplus air may be conducted by a pipe 18 to any place to utilize the heat for instance to warm rooms or goods.

The superheater 12 for the air is arranged in

2

advance of the superheater 4 for the steam. The heating of the surplus of air necessary to increase the efficiency takes up much heat from the gases of combustion and the latter arrive at the steam superheater 4 at a comparatively low temperature.

To transfer the heat necessary for the superheater 4, hot gases of combustion are drawn from the combustion chamber above the grate 3 and are led by pipe 19 into the space between the air heating device 12 and the steam superheater 4 and are mixed with the gases of combustion which have already given off part of their heat to the steam boiler 1 and the air heater 12. In the pipe 19 a controlling valve 20 is arranged. The influx of the hot gases by pipe 19 is arranged in such a manner that an intimate mixture of the gases of combustion after the air heater 12 is attained.

20 In Fig. 2 a plant is shown in which hot gases are added to the gases of combustion of the steam boiler in advance of the air heater, and in which the hot gases are produced in a separate combustion chamber. The plant comprises two combustion chambers 29 and 30, one for the steam boiler A and one for the air heater. The air for the combustion is fed by the pipes 161 and 162 to the grates 31, 32. The steam turbine 6 is a back pressure turbine. The feed water is delivered by pump 8 to the preheating devices 101, 102, 103 and from the latter into the boiler 1. The exhaust gases from the steam boiler A and from the air heater B transfer part of the residual heat to the feed water. In the air turbine an intermediate reheating is made use of; the said air turbine comprises two separate turbines 131, 132 which drive a compressor 14 and any work producing machine 15. On the grate 32 sufficient fuel may be burnt to supply the necessary heat for the air heaters 121, 122. Through a pipe 191 a part of the gases of combustion of the steam boiler 1 is led to the air heater 121 and is mixed with the hot gases in advance thereof to prevent the rising of the temperature in advance of the air heater 121 to a too high degree. Through another pipe 192 gases of combustion of the steam boiler plant are led into the space between the two air heaters 121, 122. The necessary pressure drop may be produced by a fan in the conduit 161 or by a valve in the conduit 162. In the pipes 191, 192 dampers 201, 202 are arranged to control the temperature in advance of the heaters 121, 122 and keep the temperature at a predetermined height. The air discharged from the air turbine 132 is led partly to the grates 31, 32

and partly to the feed water heater 101 and from there to any other place for heating purposes.

The mounting of the steam and air heaters and the means to feed and to mix the hot gases with the gas of combustion of the steam boiler may be made in any suitable manner.

In both of the examples of the plant described more heat is fed to the air turbine plant by mix in with hot gases. The output of the air turbine might be increased still more. The efficiency of the entire plant is materially increased in comparison with a plant without the admixture of hot gases to the gases of combustion of the steam boiler.

What I wish to secure by United States Letters Patent is:

1. In a steam-air power plant, the combination with a steam generator comprising a steam boiler, a combustion chamber and steam super-heater, of an air heater arranged between said steam boiler and said steam super-heater, and means for conducting a portion of the hot gases from said combustion chamber into the combustion gases where the latter enter the zone in which said steam super-heater is arranged while the remaining hot gases heat the boiler and the air heater.

2. In a steam-air power plant, the combination with a steam generator comprising a steam boiler, a combustion chamber and a steam super-heater, of an air heater arranged between said steam boiler and said steam super-heater, a duct for conducting a portion of the hot gases from said combustion chamber into the combustion gases where the latter enter the zone in which said steam super-heater is arranged while the remaining combustion gases heat the boiler and the air heater, and means for controlling the amount of hot gases passing through said duct.

3. In a steam-air power plant, the combination, a steam generator comprising a steam boiler, a combustion chamber and a steam super-heater, an air heater arranged between said steam boiler and said steam super-heater, controllable means for conducting hot gases from said combustion chamber into the combustion gases where the latter enter the zone in which said steam super-heater is arranged, a prime mover operated by the steam produced by said steam generator, a prime mover operated by the air heated by said air heater, means for conducting a portion of the air exhausted by said last mentioned prime mover into the combustion chamber of said steam generator, a feed water preheater, means for condensing the steam exhausted by said steam operated prime mover, means including a pump for conducting the condensed water through

said preheater and into said steam boiler, and means for conducting the remaining portion of the air exhausted by said hot air operated prime mover through said preheater for heating the feed water passing therethrough.

3 10 a valve passing therethrough.

4 In a steam-air power plant, the combination, a steam generator comprising a steam boiler, a combustion chamber and a steam super-heater, an air heater arranged between said steam boiler and said steam super-heater, duct means including a valve for conducting hot gases from said combustion chamber into the combustion gases where the latter, after having given off a part of their heat to said steam boiler, enter the zone 10 in which said steam super-heater is arranged, a prime mover operated by the steam produced by said steam generator, a prime mover operated by the air heated by said air heater, means for conducting a portion of the air exhausted by said last mentioned prime mover into the combustion chamber of said steam generator, a feed water pump, a preheater for feed water, means for connecting the latter with said pump and with said boiler, and means for conducting the remaining portion of the air exhausted by said hot air operated prime mover through said preheater for heating the feed water passing therethrough.

5 In a steam-air power plant, the combination,

5. In a steam-air power plant, the combination with a steam generator comprising a steam boiler, a combustion chamber below said steam boiler and a steam super-heater in a zone above said steam boiler, of an air heater arranged in another zone above said steam boiler, and means for conducting a portion of the hot gases from said combustion chamber into the combustion gases where the latter enter the zone in which said steam super-heater is arranged.
